FURNITURE ASSEMBLY
Paul Eugene Amos, 1132 Pennsylvania Ave.,
McKeesport, Pa. 15130
Filed Jan. 16, 1969, Ser. No. 791,742
Int. Cl. A47c 3/04
U.S. CL. 297—462 12 Claims

ABSTRACT OF THE DISCLOSURE

A furniture assembly comprising a plurality of articles of furniture usable independently of each other, one article of furniture being stored within another article of furniture to form an assembly which is also usable as an article of furniture, each of the articles of furniture including housings having removable lids, the lids having interengaging parts for fitting opposing faces of the lids together and forming a lid entity for the assembly. The lids of the articles of furniture are so constructed that they are reversible and interchangeable thereby permitting use on either article of furniture and exposure of either face of the lid. The assembly further affords storage space for attachments used in conjunction with the articles of furniture.

BACKGROUND AND OBJECTS

It is often desirable to have available for occasional use several pieces of furniture of the hassock type or the like, which pieces are frequently removed from view when not in use. The storage of these comparatively bulky articles of furniture presents a problem because of the lack of such storage space in the average home.

It is an object of this invention to provide a furniture assembly including a plurality of articles of furniture stored one within the other, the assembly being adaptable for use in its assembled state or disassembled for use of the individual pieces of furniture.

Another object is to provide a plurality of hassocks or the like stored one within the other, each hassock embodying removable lids, the lids having complementary interfitting parts which, in their interengaged state form a lid entity for the assembly.

A further object is to provide a furniture assembly of the character described wherein the lids are reversible for selective exposure of either face of the lids, the lids being applicable to either of the hassocks.

A further object is to provide a furniture assembly as described including attachments adapted to be stored within the assembly for selective use with the articles of furniture.

Other objects of the invention will be understood from the following description of the presently preferred form of the present invention.

DESCRIPTION OF FIGURES OF DRAWINGS

FIG. 1 is a perspective view of the furniture assembly of the present invention;

FIG. 2 is a perspective view of an article of furniture forming a part of the furniture assembly of FIG. 1;

FIG. 3 is a perspective view of an article of furniture forming another part of the furniture assembly of FIG. 1;

FIG. 4 is a view similar to FIG. 2 showing the lid of the article of furniture reversed;

2

FIG. 5 is a view similar to FIG. 3 showing the lid reversed;

FIG. 6 is a view similar to FIG. 4, and illustrating the adaptation of the lid for the reception of a tray;

FIG. 7 is a perspective view of the article of furniture illustrated in FIG. 2, showing to advantage the adaptation thereof for the reception of a plurality of leaves;

FIG. 8 is a fragmentary plan view of one of the leaves illustrated in FIG. 7;

FIG. 9 is a sectional view taken along the lines 9—9 of FIG. 1 looking in the direction of the arrows;

FIG. 10 is a sectional view taken along the line 10—10 of FIG. 4, looking in the direction of the arrows; and

FIG. 11 is a sectional view taken along the line 11—11 of FIG. 5 looking in the direction of the arrows.

DESCRIPTION OF FIGURES OF THE DRAWING

In FIG. 1, there is illustrated the furniture assembly of the present invention which is generally designated 20, which comprises articles of furniture generally designated 22 and 24 which are illustrated in FIGS. 2 and 3. For purposes of illustration, furniture assembly 20 is in the form of a hassock, and articles of furniture 22 and 24 are also of the hassock type. Although the assembly and the articles are illustrated as being of oval shape, any other suitable shape may be employed.

Hassock 22 includes a housing 26 including side and bottom walls, and legs 28 which are secured to, and depend from, the bottom walls of the housing.

30 A removable lid 32 is adapted for placement over the open upper end of the housing, and is complementary in shape thereto. The removable lid includes an oval shaped vertical wall 34 which, as shown in the drawings, is adapted for frictional engagement with the upper, inner periphery of housing 26. Intermediate the height of wall 34, there is provided an annular lateral extension of wall 34 forming a bead 36 along the outer periphery which serves as ornamentation for the hassock as well as providing an abutment or stop to limit the entry of lid 32

35 into housing 26. Within wall 34 is a solid planar surface 38, which is also disposed intermediate the height of wall 34. A cushion surface 40 is adhesively secured to or fixed in any other suitable manner within wall 34 between planar surface 38 and a terminal of wall 34. By means of this arrangement, lid 32 may be selectively placed atop housing 26 with either planar surface 38 exposed, as illustrated in FIG. 4, or with cushion surface 40 exposed, as illustrated in FIG. 2.

40 Hassock 24 includes a housing 42 comprising side and bottom walls, the side wall being provided with an annular bead 44 which is in proximate, spaced relation to the upper terminal of the housing side. A removable lid is indicated at 46 and includes an oval-shaped body portion 48, the thickness of which is approximately equal to the height of wall 34 of lid 32. An annular flange or bead 50, is affixed to the outer periphery of body portion 48, which bead is intermediate the height of the body portion. Bead 50 serves as an abutment to limit the entry of lid 46 into housing 42 when the lid is placed thereon, the outer peripheral edge of body portion 48 being in frictional engagement with the upper, inner periphery of housing 42. A cushion support 52 is affixed to one face of body 48. The opposite face of body 48 is reduced and extended to provide a planar surface which

45

50

55

is substantially the same size as planar surface 38 of lid 38. As shown to advantage in FIG. 9, this relationship enables the interengagement of lids 32 and 46 so that planar surface 54 may enter into the space between the upper terminal of wall 34 and planar surface 38 of lid 32, to form an interfitting engagement.

It is apparent from a consideration of the drawings that hassock-type members 22 and 24 are, by virtue of the reversible nature of lids 32 and 46, readily adaptable to expose either a cushion surface or a flat planar surface, thereby lending the article of furniture for either as a hassock or a small table. Also lids 32 and 46 may be interchangeably applied to housings 26 and 42.

It is further within the contemplation of the present invention to provide a tray 56, which is shown to advantage in FIG. 6, which tray may also be stored within the present assembly. It will be noted that, as depicted in FIG. 6, the tray is of a size that may be readily inserted into the space between planar surface 38 and the upper terminal of wall 34.

In FIGS. 7 and 8 there is illustrated another use of the assembly of the present invention, this being for use as a card table or the like. For this purpose, there are provided a plurality of leaves 58 of like construction, each of which leaves is provided with a central longitudinal slot 60. Leaves 58 are preferably complementary in shape to the shape of the hassock 22 to which they are applied. These leaves may be placed on top of housing 26 of hassock 22 in such a manner that a portion of each leaf extends from a different side of the hassock. Another leaf 62 is located centrally of the hassock, and may be provided with a planar surface such as checkerboard 64. A securing member 66 of any suitable type may be employed for joining leaves 58 and 60 together and holding them in fixed relationship to each other. Leaves 58 and 60 are stored within the assembly when not in use.

The assembly of the present invention is preferably of molded plastic construction, with the exterior thereof either upholstered or unupholstered as desired. However numerous structural variations may be employed within the scope of the claims hereto appended.

What I claim is:

1. A furniture assembly comprising:

- (a) a first article of furniture having a housing,
- (b) a second article of furniture having a housing removably stored in the housing of said first article of furniture,
- (c) a lid entity for positioning over the housing of said first article of furniture, said lid entity including,
- (d) a first lid unit for placement over the housing of said first article of furniture, and
- (e) a second lid unit for placement over the housing of said second article of furniture,
- (f) said first and second lid units being provided with complementary interfitting elements,
- (g) said interfitting elements being joined together to form said lid entity for the assembly.

2. The furniture assembly of claim 1, wherein each of said lid units includes:

- (a) a body portion for fitting engagement in the top of each of said housings, and
- (b) an annular bead along the outer periphery of each body portion,
- (c) each of said beads engaging the upper terminal of said housings for limiting the entry of said lid entities into said housings.

3. The furniture assembly of claim 1, wherein:

- (a) said first lid unit includes a wall of closed geometric configuration, and
- (b) a planar surface within said wall intermediate the height of said wall,
- (c) said second lid includes a body portion,
- (d) one face of said body portion being reduced and extended to provide a planar surface,

(e) the planar surfaces of said first and second lid units being substantially equal in size to permit interfitting of the reduced and extended planar surface of said second lid unit within said wall of said first lid unit into engagement with the planar surface of said first lid unit.

4. The furniture assembly of claim 2, wherein each of said lid units includes:

- (a) a pair of face members,
- (b) each of said lid units being reversible for selective exposure of either of said face members.

5. The furniture assembly of claim 3, with the addition of:

- (a) a tray complementary in shape to the planar surface of said first lid unit and adapted for engagement therewith within the wall of the first lid unit.

6. The furniture assembly of claim 3, with the addition of:

- (a) a plurality of leaves of like construction,
- (b) each of said leaves being provided with a like, longitudinal slot, and
- (c) securing means extending through the longitudinal slots of said leaves for joining the latter together in partially superimposed relationship,
- (d) said leaves being positioned on top of the housing of one of said articles of furniture with the leaves extending in different directions.

7. A furniture assembly comprising:

- (a) a first hassock including a housing and removable lid, and
- (b) a second hassock including a housing and removable lid,
- (c) the housing of said second hassock being stored within the housing of said first hassock when not in use,
- (d) the lids of said first and second hassocks having complementary, interengageable elements for joining the lids together to form a lid entity,
- (e) said lid entity being positioned on the housing of said first hassock while the housing of the second hassock is stored therein, to permit use of the assembly.

8. The furniture assembly of claim 7, wherein:

- (a) each of said housings is of complementary shape,
- (b) each of said lids includes a complementary body portion adapted to fit within the upper terminal portion of each housing, and
- (c) a bead extending around the outer periphery of said body portion and engageable with the upper edge of the housing, for limiting the entry of the lid into the housing.

9. The furniture assembly of claim 8, wherein:

- (a) each of said lids has two different faces,
- (b) said lids being reversible to selectively expose either of said faces.

10. The furniture assembly of claim 8, wherein:

- (a) the body portion of one of said lids comprises a vertical wall of closed geometric configuration,
- (b) a planar surface within said wall intermediate the height thereof,
- (c) cushioning means applied to one face of said planar surface,
- (d) one face of the body portion of the other of said lids being reduced and extend for interfitting engagement between the wall and one face of said other lid, and
- (e) cushioning means applied to the opposite face of the second lid body portion.

11. The furniture assembly of claim 10, with the addition of:

- (a) a tray complementary in shape and size to the planar surface of said first lid for placement thereon within said vertical wall.

12. The furniture assembly of claim 10, with the addition of:

- (a) a plurality of leaves of like construction,
- (b) each of said leaves being provided with a like, longitudinal slot, and
- (c) securing means extending through the longitudinal slots of said leaves for joining the latter together in partially superimposed relationship,
- (d) said leaves being positioned on top of the housing of one of said hassocks with the leaves extending in different directions.
